US00D920813S

(12) **United States Design Patent** (10) Patent No.: **US D920,813 S**
(45) Date of Patent: ** Jun. 1, 2021

(54) **INSPECTION SYSTEM**

- (71) Applicant: **Baker Hughes Oilfield Operations LLC**, Houston, TX (US)
- (72) Inventors: **Yanmin Zhan**, Shanghai (CN); **Najie Jiao**, Shanghai (CN); **Sanmao Xiong**, Xi'an (CN); **Wenhan Fu**, Shanghai (CN); **Xiaoyu Jiang**, Shanghai (CN)
- (73) Assignee: **BAKER HUGHES OILFIELD OPERATIONS LLC**, Houston, TX (US)
- (**) Term: **15 Years**
- (21) Appl. No.: **29/690,205**
- (22) Filed: **May 6, 2019**
- (51) LOC (13) Cl. **10-04**
- (52) U.S. Cl.
USPC **D10/46**; D10/75; D10/81; D10/102;
D24/186

(57) **CLAIM**

The ornamental design for an inspection system, as shown and described.

DESCRIPTION

FIG. 1 is a front view of an inspection system;

FIG. 2 is a side view thereof;

FIG. 3 is another side view thereof;

FIG. 4 is a top view thereof;

FIG. 5 is a bottom view thereof;

FIG. 6 is a front perspective view thereof;

FIG. 7 is a back perspective view thereof; and,

FIG. 8 is another front perspective view thereof.

The broken line illustration of portions of the inspection system in the drawing is for illustrative purposes and is not part of the claimed design.
